CLAIM

The ornamental design for a foot wedge, as shown and described.

DESCRIPTION

FIG. 1 is a perspective view, as seen from one side, of the foot wedge;

FIG. 2 is a top view of the foot wedge of FIG. 1, additionally showing a “toe tag” as environmental structure;

FIG. 3 is a first side view of the foot wedge of FIG. 1;

FIG. 4 is a second side view of the foot wedge of FIG. 1;

FIG. 5 is a front view of the foot wedge of FIG. 1;

FIG. 6 is a rear view of the foot wedge of FIG. 1; and,

FIG. 7 is a bottom view of the foot wedge of FIG. 1.

In FIGS. 1 through 7, dashed lines indicate environmental structure that forms no part of the claimed design.
